UNITED STATES PATENT OFFICE.

AARON G. BRYAN, OF EAST ST. LOUIS, ILLINOIS.

RAILWAY-TIE.

1,394,272.

Specification of Letters Patent.

Patented Oct. 18, 1921.

Application filed December 13, 1920. Serial No. 430,221.

To all whom it may concern:

Be it known that I, AARON G. BRYAN, a citizen of the United States, residing at the city of East St. Louis, in the county of St. Clair and State of Illinois, have invented certain new and useful Improvements in Railway-Ties, of which the following is a specification.

This invention is a metallic railroad tie, 10 and comprises the tie itself, pillowblocks for the rails, and means for attaching the rails to the ties.

The object of this invention is to cheapen railroad construction, to provide an efficient 15 substitute for wooden ties now becoming scarce, to lessen the noise, and to accommodate expansion and contraction due to heat and cold.

In the accompanying drawings, forming 20 part of this specification, in which like numbers of reference denote like parts wherever they occur,

Figure 1 is a transverse section through a line of track showing the parallel rails and 25 pillowblocks in cross-section, but the tie in longitudinal section;

Fig. 2 is a top plan view of the same;

Fig. 3 is a view from one side of the rail 30 of the means for attaching the rail to the tie;

Fig. 4 is a similar view on the opposite side of the rail of the same tie taken on the line 4—4 in Fig. 1, looking in the direction of the arrows;

Fig. 5 is a top plan view of a rail joint 35 with tie embodying this invention;

Fig. 6 is a sectional view on the line 6—6 in Fig. 1;

Fig. 7 is a modification of this invention, 40 and is a transverse section through a rail and pillowblock, but with the tie in longitudinal elevation; and

Fig. 8 is an end view of a rail and tie as 45 shown in the modification in Fig. 7.

The tie proper 1 has a depending rib or flange or flanges 2 containing cutaway parts or notches 3.

In the top of tie 1 openings 4 are provided, allowing the suspension therein of 50 metal boxes 5 by means of flanges or projections 6. The edges 7 of openings 4 are suitably depressed, so that flanges or projections 6 are countersunk therein.

In each box 5 is placed a wooden block 55 8 or other suitable cushion on which rests

the base of the rail 9, the block 8 being preferably slightly higher than box 5 is deep and substantially the same width as the base of rail 9.

Lugs on plate 10 and rivets 11 serve to 60 fasten flange 2 to the upper part or tie proper 1.

A projection 12 passes upwardly through notch 13 in tie 1, and a cotter pin 14 passing through a perforation 15 in projection 65 12 binds certain parts in position. Projection 12 is integral with or attached to rib or flange 2.

A locking-plate 16 preferably on the outside of rail 9 is of such size that its jaws 70 17 and 18 grip, respectively, the edge of the base of rail 9 and the lower edge of box 5 and are forced into locking engagement to maintain such grip by key 19, which extends downwardly (as does, also, plate 16) 75 through notch 13, the forked upper part 20 of key 19 passing on both sides of projection 12 and cotter 14 binding all said parts in locking position. The plate 16 of itself is a loose member except as fastened in 80 place, first by key 19, and secondarily by cotter 14. Key 19 forms a tight contact with plate 16, so as to force the jaws 17 and 18 of plate 16 tightly to grip the base of rail 9 and the bottom of box 5. If desired, key 19 may possess the form of a wedge. Cotter 14 is preferably in the form of a split pin, the ends of which can be bent as shown in Fig. 2, so as to remain tight in spite of vibration. The fork 20 is 85 preferably curved, as shown in Fig. 1, so as to afford a seat 21 for cotter 14.

On the opposite side of rail 9, a locking-plate 22, having jaws 23 and 24, is provided with notch 25, in which wedge 26 can 90 be driven home to bind jaw 23 tightly upon the base of rail 9 and jaw 24 tightly upon the underneath side of wedge 26. A locking screw 27 or the like fixes wedge 26 in 95 place. This completes the fastening of rail 100 9 to tie 1.

Plates 16 and 22 are substantially similar with the exception of notch 25 in the latter. In use the bottom jaw 18 of plate 16 takes hold of the bottom of box 5, while the corresponding jaw 24 of plate 22 bites the underneath side of wedge 26.

As shown in Fig. 5, a plurality of these ties is preferably used at joints between the ends of rails 9, one of these ties under- 110

lying or spanning such joint 28 and each of the rails 9 being clamped to one other such tie on each side thereof.

5 The wedge 26 slides closely along one side of box 5 and through a suitable notch 28 in rib or flange 2.

In the modification shown in Figs. 7 and 8, there is a plurality of flanges 2 secured to the tie, a similar plate or lug 10 being held by bolts or rivets 11. The difference is that the recess or cutaway portions 3 are omitted in the modification, and a small hole 29 is used to pass the wedge 26 through to locking bolt 27, which is secured on the 15 outside of the second flange or rib 2 as at 30. The second rib 2 in Fig. 8 also has a corresponding hole 31 through which passes the end of the wedge 26 receiving the locking bolt 27.

20 As illustrated in the drawings and as described above, the metal boxes 5 are suspended within the openings 4. However, if desired, the boxes may be formed integral with the tie, that is, the tie and boxes 25 made in one piece.

Having thus described this invention, I hereby reserve the benefit of all changes in form, arrangement, order, or use of parts, as it is evident that many minor changes 30 may be made therein without departing from the spirit of this invention or the scope of the following claims.

I claim:

1. The combination of a tie-member and 35 a rib thereon having a projection extending through the said tie-member, a locking plate having jaws, a key, and means for fastening the said key to the said projection.

2. The combination of a tie-member and 40 a rib thereon having a projection extending through the said tie-member, a locking plate having jaws, a key, and means for fastening the said key to the said projection, the said tie-member having a opening and there 45 being a box located in the said opening and a block located in the said box.

3. The combination of a tie-member and 50 a rib thereon having a projection extending through the said tie-member, a locking plate having jaws, a key, and means for fastening the said key to the said projection, the said tie-member having an opening and there 55 being a box located in the said opening and a block located in the said box, one of the said jaws gripping the said box and the other a rail.

4. The combination of a tie-member and a rib thereon having a projection extending 60 through the said tie-member, a locking plate having jaws, a key, and means for fastening the said key to the said projection, the said tie-member having an opening and there 65 being a box located in the said opening and a block located in the said box, the said box having a projection adapted to rest upon

the material of the said tie surrounding the said opening.

5. The combination of a tie-member and a rib thereon having a projection extending through the said tie-member, a locking plate 70 having jaws, a key, and means for fastening the said key to the said projection, the said tie-member having an opening and there being a box located in the said opening and a block located in the said box, the said box 75 having a projection adapted to rest upon the material of the said tie surrounding the said opening and the edges of the said material being depressed.

6. The combination of a tie-member and 80 a rib thereon having a notch or opening therethrough, a wedge adapted to pass through the said notch or opening, and a locking plate having jaws and a notch there- 85 in through which the said wedge is adapted to pass.

7. The combination of a tie-member and a rib thereon having a notch or opening therethrough, a wedge adapted to pass through the said notch or opening, and a 90 locking plate having jaws and a notch therein through which the said wedge is adapted to pass, the said jaws gripping the said wedge and a rail.

8. The combination of a tie-member and 95 a rib thereon having a notch or opening therethrough, a wedge adapted to pass through the said notch or opening, and a locking plate having jaws and a notch therein through which the said wedge is 100 adapted to pass, the said jaws gripping the said wedge and a rail, the said tie-member having an opening and there being a box located in the said opening and a block located in the said box.

9. The combination of a tie-member and a rib thereon having a notch or opening therethrough, a wedge adapted to pass through the said notch or opening, and a locking plate having jaws and a notch 110 therein through which the said wedge is adapted to pass, the said jaws gripping the said wedge and a rail, the said tie-member having an opening and there being a box located in the said opening and a block located in the said box, there being another locking-plate on the opposite side of the rail and the said plate having jaws, one of which grips the rail and the other the said box.

10. The combination of a tie-member and a rib thereon having a notch or opening therethrough, a wedge adapted to pass through the said notch or opening, and a locking plate having jaws and a notch 125 therein through which the said wedge is adapted to pass, the said jaws gripping the said wedge and a rail, the said tie-member having an opening and there being a box located in the said opening and a block located 130

in the said box, there being another locking-plate on the opposite side of the rail and the said plate having jaws, one of which grips the rail and the other the said box, the said box having a projection adapted to rest upon the material of the said tie surrounding the said opening.

11. The combination of a tie-member and a rib thereon having a notch or opening therethrough, a wedge adapted to pass through the said notch or opening, and a locking plate having jaws and a notch therein through which the said wedge is adapted to pass, the said jaws gripping the said wedge and a rail, the said tie-member having an opening and there being a box located in the said opening and a block located in the said box, there being another locking-plate on the opposite side of the rail and the said plate having jaws, one of which grips a rail and the other the said box, there being a plurality of the said jaws gripping the said alining rails so as to span the joint therebetween.

12. The combination of alining rails and a tie underlying the joint therebetween, the said tie comprising a tie-member and a rib therefor having a notch or opening therethrough, a wedge adapted to pass through the said notch or opening, and a locking plate having jaws and a notch therein through which the said wedge is adapted to pass, the said jaws gripping the said wedge and a rail, the said tie-member having an opening and there being a box located in the said opening and a block located in the said box, there being another locking-plate on the opposite side of the rail and the said plate having jaws, one of which grips the rail and the other the said box.

13. The combination of alining rails and a tie underlying the joint therebetween, the

said tie comprising a tie-member and a rib 45 thereon having a notch or opening therethrough, a wedge adapted to pass through the said notch or opening, and a locking plate having jaws and a notch therein through which the said wedge is adapted to 50 pass, the said jaws gripping the said wedge and a rail, the said tie-member having an opening and there being a box located in the said opening and a block located in the said box, there being another locking-plate 55 on the opposite side of the rails and the said plate having jaws, one of which grips a rail and the other the said box, there being a plurality of the said jaws gripping the said alining rails so as to span the joint there- 60 between.

14. The combination of alining rails and a tie underlying the joint therebetween, the said tie comprising a tie-member and a rib thereon having a notch or opening therethrough, a wedge adapted to pass through the said notch or opening, and a locking plate having jaws and a notch therein through which the said wedge is adapted to 65 pass, the said jaws gripping the said wedge 70 and a rail, the said tie-member having an opening and there being a box located in the said opening and a block located in the said box, there being another locking-plate 75 on the opposite side of the rails and the said plate having jaws, one of which grips a rail and the other the said box, there being a plurality of the said jaws gripping the said alining rails so as to span the joint there- 80 between and there being another tie of the same kind on each side of the said first-mentioned tie and reinforcing the same and the jaws of which respectively grip only one of the said rails.

In testimony whereof I hereunto affix my 85 signature.

AARON G. BRYAN.
